(57) **CLAIM**

The ornamental design for a descaler cleaner with large nozzle head as shown and described.

DESCRIPTION

FIG. 1 is a front perspective view of a descaler cleaner with large nozzle head;

FIG. 2 is a rear perspective view of the descaler cleaner with large nozzle head;

FIG. 3 is a front elevation view of the descaler cleaner with large nozzle head;

FIG. 4 is a rear elevation view of the descaler cleaner with large nozzle head;

FIG. 5 is right side view of the descaler cleaner with large nozzle head;

FIG. 6 is a left side view of the descaler cleaner with large nozzle head;

FIG. 7 is a top view of the descaler cleaner with large nozzle head; and,

FIG. 8 is a bottom view of the descaler cleaner with large nozzle head.

The various components shown in broken line illustrations are shown in broken lines for environmental illustrative purposes only and form no part of the claimed design.

1 Claim, 7 Drawing Sheets
